METHOD OF CONCENTRATION

Clarence L. Dunn, Berkeley, Mott Souders, Jr., Piedmont, and Cornelius Groot, Berkeley, Calif., assignors to Shell Development Company, San Francisco, Calif., a corporation of Delaware

Application August 20, 1945, Serial No. 611,650

12 Claims. (Cl. 260—302)

1

This invention relates to a process for recovering and concentrating unstable organic compounds. More particularly, it deals with the transfer of unstable organic compounds between different liquid media. Still more particularly, it deals with the transfer of unstable acid-acting organic compounds from an organic solvent solution to an aqueous medium which is susceptible to ready handling and concentration.

It is an object of this invention to recover and concentrate—simply, effectively, quickly and economically—unstable acid-acting organic compounds from their organic solutions. Another object is to avoid the use of a slurry in producing a salt of a relatively water-insoluble base and an unstable organic acid. Another object is to concentrate quickly and economically a liquid medium possessing a low content of a relatively non-insoluble inorganic salt of an antibiotic, such as penicillin. Another object is to produce a relatively stable salt of penicillin. Another object is to concentrate quickly and efficiently antibiotics in highly diluted solutions. Another object is to extract an unstable acid-acting organic compound from organic solvent solutions with a true aqueous solution of an alkaline earth metal base and concentrate the resulting aqueous phase of said compounds by recirculation through a flash evaporator, prior to sublimation to dryness. Still other objects of this invention will appear from time to time in the following description.

Some of the unstable organic compounds comprehended by this invention are: ketocarboxylic acids, acrylic and alkyl acrylic acids, picric acid, certain hormones, certain vitamins, and certain antibiotics such as penicillin. For a discussion of the sources of antibiotic substances, reference is made to "Endeavor" (Kynock Press, London) Vol. 3, No. 9, January, 1944, pp. 3-14.

As illustrative of the application of this method, reference will now be made to the treatment of penicillin.

In order to separate penicillin from mold and/or impurities naturally associated with it, it is customary to go through an extraction process with an organic solvent for penicillin whereby a solution of relatively pure penicillin in the solvent is eventually obtained. In the last step of the recovery process, the penicillin is transferred back into water in the form of its sodium salt by extraction from the solvent solution with an aqueous sodium bicarbonate solution. Heretofore, it has been customary to charge the final aqueous solution of penicillin salt into ampules and then sublime the bulk of the water therefrom at very

2

low subatmospheric pressure at or below a temperature of about 0° C. However, this procedure is not practical in the last step with dilute solutions of relatively water-insoluble inorganic bases such as alkaline-earth metal hydroxides.

The installations which are required for drying the water-soluble salt solutions of much higher concentrations are already very cumbersome. As these solutions have a tendency to foam on boiling, evaporation must proceed very slowly. Hence excessive time would be required in concentrating highly dilute, relatively water-insoluble salt solutions by this method. Moreover, it would not be possible to introduce the standard charge of 100,000 Oxford units (see article by Florey and Jennings in British Journal of Experimental Pathology, volume 23, page 120, of June, 1942) into standard ampules when using such relatively highly dilute solutions.

Despite these adverse factors, the calcium salt of penicillin is preferred over the sodium form due to the greater stability and lower relative toxicity of the former. However, a strong interest has prevailed for the manufacture of the calcium salt.

Previously, in order to overcome the stated difficulties, slaked lime was added directly with water, or in the form of an aqueous slurry, to the organic solvent containing the penicillin so that a final aqueous solution of the calcium salt of penicillin could be obtained of sufficient concentration to be charged directly to the ampules for sublimation of the bulk of the water. In a continuous process these procedures also had their disadvantages, namely that the rate of flow, i. e. the pumpability and passage through rotameters, etc., and the concentration of the calcium oxide or of the calcium hydroxide could not be easily controlled to prevent an excess of calcium base in the final product which excess if present would quickly deactivate the penicillin associated therewith. On the other hand, with insufficient calcium base, penicillin is left behind in the solvent and the aqueous penicillin solution is unstable.

It has now been discovered that dilute aqueous solutions of penicillin alkaline-earth metal salts can be concentrated rapidly to produce salt solutions of high potency and stability which, when filled into ampules, can be evaporated to dryness in a relatively short time under low subatmospheric pressure without resorting to a solid base (or a slurry thereof) by the combination of steps disclosed hereinafter. In this manner processing time and equipment can be most efficiently utilized with no loss of penicillin. These steps com-

prise: (1) extraction of the penicillin from its organic solvent solution with a true aqueous solution of an alkaline-earth metal base to produce two phases: an organic solvent phase and an aqueous phase containing the corresponding penicillin salt and (2) flash vaporizing the bulk of the water from the aqueous phase by recirculating it through a flash evaporator. The resulting concentrate, if then desired, may be introduced directly into an ampule for final sublimation.

As a consequence of this invention, one can use a dilute solution of an aqueous alkali-earth metal basic compound instead of a slurry of an alkaline earth metal oxide whereby local high concentrations of base are avoided with the concomitant avoidance of the deactivation of the penicillin. Another advantage of being able to use such a dilute solution for the extraction is that a better and more complete extraction of the penicillin from the organic solvent solution may be obtained because of the better phase ratio.

In order to better illustrate the process of this invention, reference is had to the accompanying drawing which shows a schematic flow diagram of an embodiment of the invention for recovering penicillin from its solution in an organic solvent such as chloroform and/or methyl isobutyl ketone, amyl acetate, acetone, and concentrating the recovered aqueous solution thereof.

In the drawing, the organic solvent solution of penicillin is introduced into the mixer 10 through valved line 11 where it is admixed with an aqueous solution of calcium hydroxide introduced through line 12. The resulting mixture is then passed through line 13 to settler 15 wherein the aqueous phase and solvent phase are separated. The solvent phase, which may still contain a small portion of the penicillin, may be withdrawn through bottom line 16 into mixer 20 where it is again admixed with more aqueous base introduced through line 22. The resulting mixture is then passed through line 23 into settler 25 from which the solvent is withdrawn through bottom line 26, and may be recovered for use again in the previous extraction of the penicillin from aqueous solutions. The aqueous phase removed from the top of settler 25 may be passed through line 24 which joins with line 12 entering mixer 10 or a portion or all thereof may be passed through line 26 into surge tank 30. In this manner a countercurrent two-stage extraction is obtained. These mixers and settlers may be replaced by a countercurrent liquid-liquid extraction column if desired.

The resulting aqueous solution of the inorganic salt of penicillin is withdrawn from the top of the settler 15 through line 14 and is introduced into the surge tank 30 from which it is continuously or intermittently withdrawn through valved line 31 into the liquid recycle line 41 and thence into the heat exchanger 40 of the concentrator 50. Circulation of the aqueous solution in the concentrator 50 is based on the principle of a thermosyphon. The heat exchanger comprises a series of tubes or similar means for indirect heat exchange of the aqueous penicillin solution with a suitable heat transfer medium. In this case, the heat transfer medium is introduced through line 43, passes down through the vertical tubes in the chamber on the left-hand side of the heat exchanger 40 and up through the vertical tubes on the right-hand side thereof, out through line 44 and into the bottom inlet of the bottom inlet 45 of the jacket around the chamber and out of the jacket through top outlet line 46.

In the heat exchanger 40, the aqueous solution

is heated to a vaporizing temperature and passed through upper vapor line 51 into flash chamber 55 where the vapors rise through the vapor knock-back section 56 and are withdrawn through line 57 into the evacuating means 60. The aqueous solution is circulated through the concentrator until it is of sufficient concentration to be charged directly into the ampules. At this time it is withdrawn through bottom valve line 53 and charged to said ampules for evaporation to dryness by sublimation as the final penicillin salt product.

Since penicillin decomposes very easily at temperatures above about 0° C. it is desirable that the described operations be carried out as close to 0° C. as possible without freezing the water present and be below about 20° C. In the concentrator 50, the aqueous solution of penicillin salt is continuously and rapidly circulated or agitated to maintain uniform conditions throughout the solution, whereby heat transfer is improved and local hot spots and precipitation are prevented. The indirect heating medium employed in heat exchanger 40 may be of any suitable type such as water, alcohol, brine solutions, which are stable under the operating conditions and is at a temperature slightly higher (preferably under 50° C. and especially below 30° C.) than the circulating solution of penicillin salt.

The evacuating means 60 may comprise a steam 30 evacuator, or may be a carbon dioxide-cooled condenser in series with an oil vacuum pump, or may be any other suitable means for maintaining a sufficiently low pressure in the concentrator to vaporize water at the temperature maintained in 35 the concentrator 50. For penicillin, the pressure is maintained between about 4.5 and 20 mm. of mercury, and preferably between about 5 and 6 mm. of mercury.

The operation of the concentrator 50 may be 40 batchwise or continuous. As a rule, batch operation is preferred when control of continuous operation is difficult due to the long time required for assaying the strength of the solution. Normally, the content of penicillin in a charge is 45 determined and the volume of the concentrate having the desired strength is calculated. Then the charge is circulated through the apparatus until the calculated volume of the concentrate has been reached.

When batch operation is resorted to, one may use the water flushing line 59 for washing out the knockback section 56 after a batch has been sufficiently concentrated.

Example

60 liters of chloroform containing 1,405 Oxford units of penicillin per ml. were extracted in a two-stage mixer and settler system as shown in the drawing, with an aqueous saturated solution 60 of calcium hydroxide. The resulting 10.28 liters of aqueous phase assayed 7,960 Oxford units of the calcium salt of penicillin per ml. This aqueous solution was then circulated through a concentrator as shown in the drawing, until the aqueous solution was concentrated to a volume of a strength corresponding to 45,000 Oxford units of the calcium salts of penicillin per ml. The indirect heating medium in the heat exchanger 65 40 was water which was maintained at a temperature of 24° C. and maintained a temperature of about 20° C. in the aqueous solution in the concentrator 50. An absolute pressure of about 17 mm. of mercury was maintained in the flash chamber by an oil pump connected to line 57 70 through a cold-trap.

The invention claimed is:

1. A process for producing an alkaline-earth metal salt of penicillin from its solution in an organic solvent comprising intimately contacting said organic solvent solution with an aqueous solution of an inorganic alkaline-earth metal base to produce an organic solvent phase and an aqueous phase containing the bulk of the said penicillin as an alkaline-earth metal salt, separating said phase, circulating said aqueous phase through a flash vaporizing zone until a major portion of the water content is evaporated from said aqueous phase, and withdrawing the resulting aqueous concentrate from said circulating system.

2. The process of claim 1, wherein said base is calcium hydroxide.

3. The process of claim 1, wherein said aqueous solution which is initially contacted is saturated with the inorganic alkaline-earth metal base.

4. A process for producing an alkaline-earth metal salt of penicillin from an organic solution of penicillin, comprising countercurrently contacting said solution with an aqueous solution of an inorganic alkaline-earth metal base to produce an organic solvent phase and an aqueous phase containing the bulk of the salt of penicillin corresponding to said base, separating said phases, flash evaporating a portion of the water content of said aqueous phase by circulating it through a heating zone in indirect heat exchange with a heat transfer medium and through a vapor disengaging zone maintained at a sufficiently low pressure to evaporate at least a portion of the water from said vapor during each cycle, and withdrawing the resulting concentrate of the alkaline-earth metal salt of penicillin from the circulating system.

5. The process of claim 4, wherein said heat transfer medium is maintained at a temperature between about 0° C. and 50° C.

6. The process of claim 4, wherein said pressure is below about 20 mm. of mercury.

7. The process of claim 4, wherein said alkaline-earth metal base is calcium hydroxide.

8. A process for producing and concentrating a salt of penicillin comprising contacting a solution of penicillin in an organic solvent with an aqueous solution of an inorganic alkaline-earth metal base to produce an organic solvent phase and an aqueous phase containing an alkaline-earth metal salt of penicillin, separating said solvent phase from said aqueous phase, flash evaporating a portion of the water content from said aqueous phase by circulating it through a heating zone in indirect heat exchange with a heat transfer medium having a temperature below about 30° C. and through a vapor disengaging zone maintained at a sufficiently low pressure to cause said evaporation to take place below about 30° C., continuing said circulation until a major amount of the water content is evaporated

from said aqueous phase, and withdrawing the resulting concentrate of the penicillin salt from the circulating system.

9. A process for producing an alkaline-earth metal salt of penicillin from its solution in an organic solvent, comprising contacting said organic solvent solution with an aqueous solution of an alkaline-earth metal hydroxide to produce an organic solvent phase and an aqueous phase containing the bulk of the penicillin as an alkaline-earth metal salt, separating said phases, circulating said aqueous phase through a flash vaporizing zone until a major portion of the water content is evaporated from said aqueous phase, withdrawing the aqueous concentrate from said circulating system and introducing it into a container, and subliming the remaining water from said concentrate to produce a substantially dry alkaline-earth metal salt of said organic solute in said container.

10. A process for producing an alkaline-earth metal salt of penicillin from an organic solution containing penicillin, comprising the steps of intimately contacting said organic solution with an aqueous solution of an alkaline-earth metal hydroxide to produce an organic solvent phase and an aqueous phase containing the bulk of said penicillin, separating the phases, circulating said aqueous phase through a heating zone wherein the aqueous phase is heated by indirect heat exchange with a heat transfer medium maintained at a temperature between about 0° C. and 50° C. and through a flash vaporizing zone while maintaining within said zone a temperature between about 0° C. and 20° C., and a pressure below about 20 mm. of mercury, and withdrawing the resulting concentrate of the alkaline-earth metal salt of penicillin from the circulating system.

11. The process according to claim 10 wherein the heat transfer medium is maintained at a temperature below 30° C.

12. The process according to claim 10 wherein the aqueous solution of a basic-acting alkaline-earth metal compound is substantially saturated 45 solution of calcium hydroxide.
